UNITED STATES PATENT OFFICE.

ABRAM JACOBSON, OF LANESVILLE, MASSACHUSETTS.

ELECTRIC SWITCH.

1,030,185.

Specification of Letters Patent. Patented June 13, 1912.

Application filed December 4, 1911. Serial No. 663,687.

To all whom it may concern:

Be it known that I, ABRAM JACOBSON, a citizen of the United States, residing at Lanesville, in the county of Essex and State 5 of Massachusetts, have invented certain new and useful Improvements in Electric Switches; and I do hereby declare the following to be a full, clear, and exact description of the invention, such as will enable 10 others skilled in the art to which it appertains to make and use the same.

This invention relates to switches, and has for its object to construct a switch which will permit a new set of batteries to 15 be switched into the circuit, namely, the circuit in connection with the internal combustion engines, without previously removing the old or worn batteries from the circuit.

20 It is a further object of the present invention to provide a means whereby the circuit may be changed from the magneto to the batteries, and vice versa without causing a miss in the fire of the engine during the 25 change.

With the above and other objects in view, this invention consists in the construction, combination and arrangement of parts, all 30 as hereinafter more fully described, claimed 35 and illustrated in the accompanying drawings, wherein:

Figure 1 is a perspective view of a switch constructed in accordance with the present invention; and Fig. 2 is a transverse section 35 taken along line 2—2 of Fig. 1.

The switch forming the subject matter 40 of the present invention comprises a plate of insulating material provided at each corner with a spring or other suitable contact member. A pair of switch contact members are centrally provided for the plate, each contact member having rigidly secured thereto a horizontal bar. The corresponding end of these horizontal bars have a switch 45 pivotally connected thereto, as will herein-after be more fully described.

Reference being had more particularly to the drawings, 10 indicates an insulating plate of any suitable non-conductive material, said plate having at the transverse terminals thereof the contact fingers 11 and 11^a, one set of contact fingers 11 leading to either the magneto (not shown) or a new set of batteries, while the contact members 11^a are 55 connected to the wires leading to the original set of batteries.

Centrally disposed with respect to the aligned contact members 11 and 11^a, on each longitudinal side of the plate 10, is a central contact member 12. These contact members 80 are connected with wires which lead to the spark plug of the internal combustion engine in any suitable way. Each contact member 12 has rigidly secured therein a bar 13 which has its terminals 13^a and 13^b offset 85 inwardly, as illustrated in Fig. 1. A switch 14 is pivoted to the terminals 13^b of the bars 13 through the instrumentality of the arms 14^a of said switch, and is of such construction that said arms are adapted to engage 70 the contact members 11. A similar switch 15 is pivotally connected to the terminals 13^a of the bar 13 through the medium of the arms 15^a of said switch, said arms adapted 75 to be engaged by the contact members 11^a.

From the foregoing it will clearly be seen that when the elements of the device are in the positions as illustrated in Fig. 1, the current flows from the original set of batteries (not shown) to the contact posts or members 11^a through the arms 15^a, through the terminals 13^a of the bars 13 and contact members 12, and thence to the ignition device of the engine. When it is desired to change from the original set of batteries to 80 the magneto or to a new set of batteries when the original set becomes useless, the switch 14 is moved downwardly until the arms 14^a thereof engage the contact members 11. This movement is made previous 85 to the removal of the switch 15 from engagement with the contact members 11^a. Thus, when the switch 14 is engaged by the contact members 11^a the current will flow from 90 said contact members, to the arms 14^a of said switch, the terminals 13^b of the contact members 12 and thence to the ignition device of the engine not shown. It will clearly 95 be understood that by the provision of this double switch it is impossible for the engine 100 to miss fire while transferring from one series of electrical supply to another, as is the case when a single switch is used.

Having thus fully described my invention, what I claim as new, and desire to secure 105 by U. S. Letters Patent, is:

In a switch, the combination with a base 110 constructed of insulating material, contact members located centrally and adjacent to the longitudinal sides of said base, a bar carried by each central contact member substantially parallel to the longitudinal sides

of said base having the terminals thereof offset inwardly, a contact post located adjacent to each corner of said base, each pair thereof along the longitudinal sides of the base being in direct alinement with one of the central contact members, and independently operating switches carried by the offset terminals of said bars, each switch adapt-

ed to coöperate with one pair of corner contact posts.

16

In testimony whereof I affix my signature in presence of two witnesses.

ABRAM JACOBSON.
